UNITED STATES PATENT OFFICE.

CHRISTOPHER C. SHELBY, OF NEW YORK, N. Y.

CUFF-HOLDER.

SPECIFICATION forming part of Letters Patent No. 320,404, dated June 16, 1885.

Application filed April 7, 1885. (No model.)

To all whom it may concern:

Be it known that I, CHRISTOPHER C. SHELBY, of the city, county, and State of New York, have invented certain new and useful 5 Improvements in Cuff-Holders; and I do hereby declare the following to be a full, clear, and exact description of the same, reference being had to the accompanying drawings, forming a part of this specification, and to the figures 10 and letters of reference marked thereon.

Heretofore cuff holders or adjusters have been constructed of a piece of metal with a clasp at each end adapted to hold the cuff rigidly to the shirt-sleeve of the wearer; but 15 this form is objectionable for several reasons, and it is therefore the object of my invention to provide an improved cuff holder or adjuster that will hold the cuff securely and at the same time will permit of a limited movement 20 of it; and the invention consists in certain novel details of construction which I will now proceed to describe.

In the drawings, Figure 1 is a perspective view showing the application of my improved 25 cuff-holder. Fig. 2 is a longitudinal sectional view of the device.

Similar letters of reference in the several parts indicate like parts.

A represent two metal clasps, consisting 30 of the jaws *a b*, pivoted together and having the spring *C* for keeping the jaws closed. Each of the jaws *b* of the clasp are provided with a portion, *d*, formed with it, or consisting of a 35 separate piece of metal attached to said jaw by soldering or otherwise.

represents a spiral spring, preferably flattened, as shown, and the portions *d* of the clasps are encircled by said spring and are secured thereto at opposite ends, by being turned over one or more coils of the spring, 40 thus forming a spring-connection between the clasps, so that when the clasps are separated the spring will be compressed, as shown in dotted lines in Fig. 2, and when they are released the spring will draw the clasps together, 45 as shown in full lines in said figure.

The operation of the device will be evident from an inspection of Fig. 1.

One of the clasps is adapted to be connected to the wearer's shirt-sleeve and the other to 50 the cuff, forming an elastic though perfectly secure connection between them.

This cuff-holder consists of few parts, can be manufactured very cheaply, and possesses 55 advantages over the old rigid connection which will be evident upon inspection.

I claim as my invention—

As an improved article of manufacture, the herein-described cuff-holder, consisting of the spiral spring and the two clasps, each clasp 60 having the rear portion of one of its jaws prolonged to form a shank which extends through the spring in opposite directions and connected to it at one end by being bent around one or more of the coils of the same, substantially as described. 65

CHRISTOPHER C. SHELBY.
